(57) **CLAIM**

The ornamental design for a strap with reflective strip, as shown and described.

DESCRIPTION

FIG. 1 is a side view of a strap with reflective strip showing my new design;

FIG. 2 is a perspective view thereof;

FIG. 3 is a top plan view thereof;

FIG. 4 is a front view thereof;

FIG. 5 is a rear view thereof;

FIG. 6 is a left side elevational view thereof; and,

FIG. 7 is a right side elevational view thereof.

The broken line showing of the human form in FIG. 1 is for illustrative purposes only and forms no part of the claimed design.
